UNITED STATES PATENT OFFICE.

JOSEPH CHENEY BAKER, OF SYRACUSE, NEW YORK.

WARM-AIR DISTRIBUTOR FOR FURNACES.

Application filed June 27, 1928. Serial No. 288,567.

This invention relates to a warm air distributing device for furnaces of the house heating type in which the heater proper is usually surrounded by an air jacket having a cold air inlet at or near the bottom and a plurality of warm air outlets leading from the top or dome of the outer case to the several rooms to be heated.

It is well-known that in furnaces of this character the warm air accumulating in the distributing chamber or dome of the jacket is more or less unevenly distributed through the several outlet pipes depending somewhat upon the exposure of the room to be heated, the difference in the lengths and sizes of the pipes and the position of the room to be heated relatively to the furnace, but in all cases the heated air will usually follow the course of less resistance either through the larger pipes or through those leading to the rooms more nearly directly over and closer to the heater thereby depriving other rooms of sufficient heat.

The main object of the present invention is to provide automatic means actuated by the upflowing current of air from around the heater to the distributing chamber of the jacket for collecting and projecting the heated air more uniformly to all of the distributing pipes.

In other words, I have sought to obtain this even distribution as simply and economically as possible by the use of a comparatively light supplemental dome rotatably mounted between the upper ends of the heater and jacket and provided with a plurality of relatively large delivery nozzles or pipes arranged in uniformly spaced relation about the axis of rotation substantially tangent to a circle passing through the bases thereof and also inclined vertically at an angle to said axis with their outer discharge ends disposed in substantially the same horizontal plane as the inner ends of the distributing pipes leading from the jacket so that the heated air impinging against the upper inclined walls of the nozzles will produce a slow rotation of the supplemental dome for the purpose of projecting the heated air accumulated in said supplemental dome into and through the distributing pipes as the nozzles are successively registered therewith during such rotation.

Other objects and uses relating to specific

parts of the distributing device will be brought out in the following description.

In the drawings:

Figure 1 is a vertical sectional view of the upper portion of a furnace and my improved warm air distributor therein.

Figure 2 is a horizontal sectional view through the upper portion of the furnace just below the top of the distributing chamber and at about the level of the inner ends of the distributing pipes showing my improved distributor in operative position.

Figure 3 is a side elevation of the detached warm air distributor as an article of manufacture adapted to be installed in a furnace.

In order that the invention may be clearly understood I have shown a portion of a heater —1— surrounded by a jacket or casing —2— to form an intervening air chamber —3— into which the cold air is adapted to enter, preferably near the bottom thereof to be heated by the heater and then collected in the distributing chamber or dome as —4— of the casing —2—.

The heater is shown as provided with a supplemental heating flue —5— near the top thereof but mainly in spaced relation to the upper portion of the heater so as to overhang the upper portion of the air chamber —3— in spaced relation to the top thereof thus permitting the heated air to flow upwardly within and around the supplemental heating chamber —5— to increase the temperature of the air entering the distributing chamber —4—.

The chamber —4— is provided with a closed top —6— in the form of an inverted cone having its apex directly over the center of the top of the heater —1— thereby forming the heating-receiving chamber or warm air dome —4—.

The peripheral walls of the dome —4— are preferably inclined vertically so as to converge upwardly for receiving a series of warm air distributing pipes —7— which are secured to said walls in more or less uniformly spaced relation circumferentially with their inner ends in substantially the same horizontal plane and their outer ends leading to the several rooms to be heated, said pipes being disposed at substantially right angles to the upwardly converging walls of the dome —4— and are, therefore, divergent upwardly relatively to the axis

of the jacket —2— to facilitate the upflow of the heated air through the pipes.

A supplemental warm air-receiving and distributing dome —8— is mounted within 5 the chamber —4— between the upper end of the heater —1— and top —6— of the casing —2— to rotate about a vertical axis substantially coincident with the axis of the heater —1— and casing —2— and comprising 10 a circular shell —9— of concavo-convex cross section centrally supported upon a vertical shaft —10— having its lower end journaled on a ball-bearing —11— on the upper end of the heater —1— and its upper end 15 journaled on the lower tapered end of a screw —12— centrally in the top wall —6— of the jacket —2— as shown in Figure 1.

The shell —9— is secured to the intermediate portion of the shaft —10— with its 20 concave side facing downwardly and in close proximity to the upper wall of the heating chamber —2— and upper end of the heater —1—.

The top wall of the shell —9— is provided 25 with a plurality of openings arranged in more or less uniformly spaced relation circumferentially about the axis of and some distance from the shaft —10— for receiving the lower ends of a plurality of warm 30 air distributing pipes or nozzles —13— having their upper outer ends open and disposed in close proximity to the upwardly converging walls of the chamber —4— and in about the same horizontal plane as the inner ends 35 of the distributing pipes —7— for delivering the heated air from the interior of the shell —9— to the several distributing pipes —7— as the supplemental dome or distributor is rotated.

40 This rotation of the shell —9— with the pipes —13— thereon is preferably effected automatically by the upflow of the heated air from the interior of the shell —9— through the pipes —13— and for this purpose the pipes —13— are secured at their 45 lower ends to the shell —9— to extend outwardly, upwardly and tangentially to a circle passing through the lower ends of the pipes in a direction opposed to the direction 50 of rotation of the distributor.

The distributor pipes —13— are also inclined upwardly and outwardly from the shell —9— in a direction opposite the direction of rotation so that the heated air 55 entering the lower open side of the shell —9— will impinge against the upwardly and laterally inclined top walls of the distributing pipes —13— with sufficient force to effect a relatively slow rotation of the distributor in the direction indicated by arrow —x—, Figure 2.

60 This rotation of the distributor causes the outer ends of the pipes or nozzles —13— to successively register with the lower inner ends of the distributing pipes —7— where-

65 by the same currents of air which effect the rotation of the distributor will be successively discharged into the distributing pipes —7—.

The shell —9— is of sufficiently large diameter to extend across the larger portion of the horizontal area of the interior of the casing —2— so as to overhang the intervening space between the heating drum —5— and dome of the heater —1— for receiving 75 and concentrating the heated air passing through the intervening space between the drum —5— and dome of the heater and directing such heated air through the discharge nozzles —13— and thence into the 80 distributing pipes —7— as the nozzles —13— are successively registered therewith.

85 It will be evident from the foregoing description that the air passing through the intervening space between the heating drum —5— and dome of the heater —1— will be heated to a higher temperature than the air in the outer portions of the casing —2— by reason of its close contact with the walls of the heater, and the placing of the shell —9— directly over this intervening space causes this highly heated air to be concentrated within the shell —9— and distributed therefrom through the nozzles —13— into the several distributing pipes —7— as the shell —9— with the pipes —13— thereon is rotated by the circulation of the heated air upwardly through the shell —9— and nozzles —13—.

90 The ball-bearing —11— rests in a concave seat in the face of a bearing member —11'— on the upper end of the dome of the heater —1— and is also engaged in a concave seat —10'— in the lower end of the shaft —10— for holding that end of the 100 shaft against lateral displacement and at the same time permitting free rotation of the shaft and distributor mounted thereon with a minimum resistance.

105 The central portion of the top —6— of the casing —2— is provided with a hub —6— having a central threaded aperture in the upper end thereof for receiving the screw-bearing —12—.

110 The lower end of the screw —12— is 115 pointed and engaged in a tapered recess in the upper end of the shaft —10— to hold that end of the shaft against lateral displacement and also to permit free rotation of the shaft with the distributor thereon 120 with a minimum amount of resistance, the screw —12— being adjustable endwise to take up wear and to facilitate the installation of the distributor between the upper end of the dome of the heater —1— and top 125 —6— of the casing —2—.

130 The distributor shell —9— and its delivery nozzles —13— are constructed and arranged in such manner as to substantially balance the distributor on its bearings

—11— and —12— under which conditions the outer ends of the delivery nozzles —13— may be arranged in quite close proximity to the peripheral walls of the chamber —4— to assure a more positive and forcible projection of the heated air from said nozzles into the delivery pipes —7— as the distributor is rotated.

The shell —9— is provided with a central hub for receiving the shaft —10—, said hub being secured to the shaft by one or more cross pins —14—, Figure 1, to assure the positive rotation of the distributor with the shaft.

15 The distributor shell —9— with the shaft —10— and nozzles —13— thereon is preferably placed in operative position upon the ball-bearing —11— before the dome or cap section of the casing —2— is placed upon 20 the main body of the casing and before the pipes —7— are secured to the dome after which the dome forming the chamber —4— and top —6— is placed over and upon the upper end of the main body of the casing 25 —2— to engage the lower end of the screw bearing —12— with the upper end of the shaft —10— whereupon the dome of the casing —2— may be secured in place followed by the placing of the pipes —7— in 30 operative connection with the dome.

When the parts are assembled in the manner described and the heater —1— is in operation the heated air passing upwardly along the outside of the heater and within 35 the chamber —3— continues to pass through the intervening space between the dome of the heater and heating drum —5— and into the shell —9— and thence into the distributing nozzles —13—.

40 This upward circulation of the air is rather rapid by reason of its highly heated condition and impinges against the upper inclined walls of the distributing nozzles —13— with sufficient force to cause a slow 45 rotation of the distributor shell —9— with the nozzles thereon while at the same time the highly heated air entering the distributing shell and nozzles passes outwardly through the nozzles and thence into the distributing pipes —7— as the nozzles are successively registered therewith during said 50 rotation thereby projecting the highly heated air of more or less uniform temperature into each of the distributing pipes leading to the several rooms to be heated, all 55 of which tends to maintain a uniform temperature in each of the rooms or at least establishing a direct flow of the heated air into each room.

60 The heating drum may be connected in any well-known manner to the smoke outlet of the heater —1— to allow the products of combustion to pass therethrough thereby materially increasing the heat radiating area of the heater and at the same time act-

ing as a baffle to divert and direct the upflowing air between the heater and casing toward the more highly heated dome of the heater and thence between said dome and drum into the overlying distributor shell —9—.

This concentration of the upflowing air against the hottest parts of the heater produces a more or less superheating of the air which accelerates its upflow between the dome and drum of the heater into the distributor shell —9— and this accelerated upflow tends to draw the air from the upper portion of the chamber —6— into the space between the drum and dome of the heater 80 for superheating the same and then directing the superheated air into the distributor shell —9— whence it flows easily and more or less rapidly through the distributing pipes —13— into the heater pipes —7—. 85

Under these conditions the impact of the upwardly circulating air against the top walls of the nozzles —13— causes the rotation of the distributor shell —9— and during this rotation the superheated air will 90 pass easily and more or less rapidly through the nozzles —13— and will be delivered at relatively high but uniform temperatures into each of the pipes —7— as the nozzles are successively registered therewith thereby 95 assuring a more uniform circulation of the superheated air to each of the rooms to which the pipes —7— are connected.

What I claim is:—

1. In a house-heating furnace having a receiving chamber for the heated air and pipes leading from said chamber to the rooms to be heated, an air distributor-shell rotatably mounted within said chamber for receiving portions of the heated air and provided with means against which the current of heated air impinges for rotating the shell, said means being arranged to direct the heated air from the interior of the shell into the pipes as the shell is rotated. 100

2. In a house-heating furnace having a receiving chamber for the heated air and pipes leading from said chamber to the rooms to be heated, a circular shell centrally journaled within said chamber to rotate 105 about a vertical axis and provided with an open lower end for receiving the heated air, said shell having outlet openings through its top wall some distance from the axis of rotation for permitting the passage 110 of the heated air from the interior to the exterior of the shell, and means extending upwardly and laterally across said openings against which the heated air impinges for rotating the shell, said means being arranged to direct the heated air from said 115 openings into the pipes as the shell is rotated.

3. In a house-heating furnace having a receiving chamber for the heated air and pipes leading from said chamber to the 120 125

130

rooms to be heated, an air distributor shell rotatably mounted within said chamber for receiving portions of the heated air and provided with a series of upwardly and laterally inclined discharge nozzles leading from the interior thereof, said nozzles having their outer ends movable across and in close proximity to the inner ends of said pipes as the shell is rotated, the shell being rotated by the impingement of the heated air against the inclined walls of the nozzles in transit therethrough.

4. The combination with a heater and an air jacket surrounding the heater in spaced relation thereto, said jacket having a top wall directly over and in spaced relation to the top of the heater to form a receiving chamber for the heated air, pipes leading from said chamber to the rooms to be heated, and a nozzle-supporting member rotatably mounted in said chamber between the upper end of the heater and top wall of the jacket and provided with a series of nozzles ar-

ranged about its axis of rotation for receiving heated air from said chambers, said nozzles being disposed at an angle to their plane of rotation to cause the impact of air thereagainst to rotate said member and having their outer ends movable across and in proximity to the inner ends of said pipes for discharging the heated air into the pipes as the member is rotated.

5. The combination with a furnace having a heater, a casing enclosing the heater in spaced relation thereto to form an air chamber, and air-distributing pipes leading from the upper portion of said chamber, of a rotary member mounted in said chamber and actuated by the heated air in transit through the chamber to the distributing pipes, said member having means for directing the heated air into the several pipes during said rotation.

In witness whereof I have hereunto set my hand this 14th day of June, 1928.

J. CHENEY BAKER.
